UNITED STATES PATENT OFFICE

WALTER H. SCHRAMM, OF PITTSBURGH, PENNSYLVANIA, ASSIGNOR TO WESTINGHOUSE ELECTRIC & MANUFACTURING COMPANY, A CORPORATION OF PENNSYLVANIA

SWITCH MECHANISM

Application filed May 26, 1927. Serial No. 194,246.

My invention relates to switch mechanism and particularly to back-of-board switchboard type switches wherein the switch mechanism is mounted behind a dead front 5 switchboard or panel.

An object of my invention is to provide a back-of-board type switch mechanism that is directly operated from the front of the board by means of an operating handle directly 10 connected to the switch blade and wherein the operating handle is disposed within a recess in the front plate of the switchboard and lies behind the front plate when in the closed position.

Another object of my invention is to provide a switch mechanism having the above noted characteristics wherein the fuse associated with the switch is accessible through an opening adjacent to the recess in the 20 switchboard, the opening being closed by a detachable cover and wherein the fuse mechanism is rendered inaccessible so long as the switch is in any other than full open position.

Another object of my invention is to provide a switchboard of the back-of-board type that is relatively simple in construction and is composed of a relatively small number of 25 parts.

Heretofore switchboards of the back-of-board type usually comprised knife switches having an operating handle pivoted to the switchboard and indirectly connected to the switch in such manner that it may be actuated by movement of the handle.

Another object of my invention is to provide a switchboard apparatus of the back-of-board type wherein the operating handle is mounted on the base carrying the switch and which is directly connected thereto and wherein the handle lies within a recess in the switchboard face when the switch is in closed position.

These and other objects that will be made 45 apparent throughout the further description of my invention, are obtained by means of the switchboard apparatus hereinafter described and illustrated in the accompanying drawings wherein;

Figure 1 is a front view of a switchboard

panel embodying features of my invention, and

Fig. 2 is a vertical section through the apparatus shown in Fig. 1 taken on the line II—II of Fig. 1.

Referring to the drawings, the apparatus includes a front plate or panel section 3 made of sheet metal and which constitutes a front face or plate of the switchboard. It will be understood that in the usual metal switchboard construction, the panels such as the panel 3 are joined at their edges to constitute a complete switchboard. The panel or front plate 3 is provided with a pair of openings 4 and 5, the lowermost being rectangular and the uppermost being of inverted T-shape. The upper recess 4 is closed by means of a cover 6 provided with a recess or pocket 7, the lower wall 8 of which is arcuate in shape and is provided with a keyhole slot 9 having 70 enlarged end portion 10, the purpose of which will hereinafter appear.

Behind the front plate 3 of the switchboard, an insulating panel 11 is mounted. The panel 11 may be secured to the frame 75 upon which the front plate is mounted or may be carried upon brackets attached to the front plate as preferred. Upon the panel is mounted a set of contact jaws 12 and a set of pivoted jaws 13 in which a set of switch 80 blades 14 are pivotally mounted for rotation about a pivoted shaft 15 which is mounted concentric with the center of curvature of the arcuate wall 8 of the closure plate 6.

As illustrated, the switch is of the 3 pole 85 type, and the blades thereof are connected at their free ends by an insulating cross bar 16 upon which an operated handle 17 is secured at the center thereof. The handle projects through the slot 9 and as illustrated in Fig. 2, occupies a position within the recess 7 and behind the front plate of the panel 90 when the switch is in the closed position illustrated in Fig. 2. The lower end of the slot 9 is enlarged at 10 to permit of the assembly 95 of the switch with respect to the front plate. It will be understood that the switch mechanism is assembled upon the insulating panel 11 before it is finally located in its permanent position. During the assembly, the operat- 100

ing handle is first moved to full open position and inserted through the enlarged end of the opening.

Fuses 18 are mounted in receptacle clips 19 that are secured to the insulated base 11, the fuses registering with the opening 5 in the panel plate 3 and are, therefore, accessible through the said opening.

The opening 5 is closed by a cover plate 21 that is detachably retained in closed position by means of clips 22 secured adjacent the lower end of the cover plate and which extend behind the cover plate in such manner that they engage the lower edge of the opening and prevent displacement of the cover. The upper edge of the cover 21 is retained in closed position by clips 23 that are engaged by a pair of pivoted latches 24 carried by the front plate or panel 3.

The latches 24 are actuated by gravity into the position in front of the clips 23 and prevent detachment of the cover 21 while in such position. The upper ends 25 of the latches 24 are inclined toward one another and are adapted to be engaged by the insulating cross bar 16 of the switch when the latter is in the full open position indicated in dotted lines in Fig. 2.

When the switch is in the full open position, the latches 24 are moved to the broken line position indicated in Fig. 1 wherein the lower ends thereof disengage from the clips 23 on the cover 21 and permit of removal of the cover plate. By reason of this interlocked construction of the switch and door, the door closing access to the fuses is retained in the closed position so long as the switch is in any position, other than the full open position.

When the switch is in the closed position, the handle 17 thereof does not extend beyond the front face of the board, and therefore cannot be engaged by foreign articles which may be brought into contact with the switchboard face. Since the handles project in front of the board when the switch is open, the handles indicate the position of the switch.

As previously stated, it has been customary to provide auxiliary levers for operating back-of-board type of switches, the operating handle being pivotally connected to the switch plate. By reason of the present construction, the operating handle may be directly connected to the switch blade, thus eliminating several parts heretofore found to be necessary and thereby correspondingly reducing the cost of manufacture. A further advantage of this type of switchboard apparatus resides in the fact that the operated handles lie within the recesses when the switches are in closed position.

It will be understood that the system embodying my invention is not limited to the specific arrangement of parts shown in the

drawings and described in the foregoing specification, as many changes and modifications may be made therein without departing from the spirit and scope of my invention, as set forth in the appended claims.

70

I claim as my invention:

1. Switch mechanism comprising a front plate having a perforate pocket in the front face thereof extending behind the front face of the plate, a knife switch pivotally maintained behind the front plate and having an operating handle extending into the pocket and lying behind the front face of the front plate when the switch is in closed position.

75

2. Switch mechanism comprising a front plate having a pocket extending behind the front face of the plate provided with an arcuate wall having a slot therein, a knife switch pivotally mounted behind the front plate and having an operating handle extending into the pocket and lying behind the front face of the front plate when the switch is in closed position.

80

3. Switch mechanism comprising a front plate having a perforate pocket in the front face thereof extending behind the front face of the plate, a knife switch pivotally mounted behind the front plate and having an operating handle extending into the pocket and lying behind the front face of the front plate when the switch is in closed position and projecting in front of the front face of the front plate when the switch is in open position.

85

4. Switch mechanism comprising a front plate having an opening therein, a cover plate for the opening having a recess extending behind the front face of the plate and provided with a perforation, a switch mounted behind the front plate and having an operating handle extending through the said perforation into the recess, the said handle lying behind the said front plate when in closed position and extending in front of the said plate when the switch is closed.

90

In testimony whereof, I have hereunto subscribed my name this 24th day of May, 1927.

WALTER H. SCHRAMM.
